Primary Examiner — Marissa J Cash*(74) Attorney, Agent, or Firm* — Martensen IP(57) **CLAIM**

The ornamental design for an unmanned cargo delivery aircraft, as shown and described.

DESCRIPTION

FIG. 1 is a top view of the unmanned cargo delivery aircraft without the cargo pod.

FIG. 2 is a view of one side of the unmanned cargo delivery aircraft without the cargo pod.

FIG. 3 is a view of the other side of the unmanned cargo delivery aircraft without the cargo pod.

FIG. 4 is a front view of the unmanned cargo delivery aircraft without the cargo pod.

FIG. 5 is a back view of the unmanned cargo delivery aircraft without the cargo pod.

FIG. 6 is a bottom view of the unmanned cargo delivery aircraft without the cargo pod.

FIG. 7 is a top view of the unmanned cargo delivery aircraft with the cargo pod.

FIG. 8 is a view of one side of the unmanned cargo delivery aircraft with the cargo pod.

FIG. 9 is a view of the other side of the unmanned cargo delivery aircraft with the cargo pod.

FIG. 10 is a bottom view of the unmanned cargo delivery aircraft with the cargo pod.

FIG. 11 is a front left perspective view of the unmanned cargo delivery aircraft without the cargo pod; and,

FIG. 12 is a front left perspective view of the unmanned cargo delivery aircraft with the cargo pod.

The broken lines shown in the drawings depict portions of the unmanned cargo delivery aircraft that form no part of the claimed design.
